UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR A FONT OF PRINTING-TYPE.

SPECIFICATION forming part of Design No. 12,637, dated December 27, 1881.

Application filed November 17, 1881. Term of patent 14 years.

To all whom it may concern:

Be it known that I, HERMAN IHLENBURG, (assignor to DAVID WOLFE BRUCE,) of the city and county of Philadelphia, Pennsylvania, have invented and produced a new and original Design for a Font of Printing-Type, of which the following is a specification.

The nature of the design is clearly shown in the accompanying typographical impression, to which reference is had; and it consists of an ornamented letter shaded upon the right and above by a heavy line followed by a lighter line. The letters proper and the heavy shaded

lines are connected at top and bottom by the short light lines, as shown. ¹⁵

The character of the design is preserved in the punctuation-marks, the numerals, and the dollar and pound-sterling symbols.

Having now described my invention, I claim— ²⁰

The design for a font of printing-type, substantially as shown and described.

HERMAN IHLENBURG.

In presence of—

A. SIDNEY DOANE,
WILLIAM V. H. HICKS.
